Arthur G. Bugler INVENTOR

INVENTOR

ATTORNEY

UNITED STATES PATENT OFFICE.

ARTHUR G. BUGLER, OF CHICAGO, ILLINOIS.

SHOE ATTACHMENT.

Application filed December 12, 1927. Serial No. 239,547.

This invention relates to certain novel improvements in shoe attachments and more particularly to a mud guard for a shoe or slipper and has for its principal object the provision of an improved construction of this character which will be highly efficient in use and economical in manufacture.

It is a known fact that particles of mud and water are thrown by shoes upon the garments of the wearer during walking or running action and it is one of the principal objects of this invention to provide a simple arrangement for preventing this throwing or splashing of mud or other particles upon the garments of the wearer during walking.

A still further object of the invention is to provide a mud guard for shoes or Oxfords having a novel and simple arrangement for permitting expeditious attachment of the guard to the heel portion of the shoe or Oxford.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a fragmentary side view of an Oxford showing my improved mud guard associated therewith; and

Fig. 2 is an under side view of the same.

Referring to the drawing, an Oxford is indicated at 10. This Oxford includes a heel 11 of the ordinary construction. My improved mud guard includes a band 12 preferably formed of elastic material and adapted to embrace the heel 11 of the Oxford 10. This band 12 is formed as an integral part of a guard body 13. This guard body 13 has an inner edge portion 14 curved to conform to the curvature of the heel portion of the shoe and in order to dispose this edge portion at a proper point with respect to the heel portion of the shoe. The top edge 15 of the band is tapered whereby to produce a narrow portion 16 which passes under the arch of the shoe.

The guard body 13 is of cup formation and when applied to the shoe is arranged in

an inverted position as best shown in Fig. 1 and along the edges 16 of the body 13 there is provided a gutter or trough 17 for the purpose of catching particles of mud and water and draining the same to the outlet ends 18 of the gutter which are disposed adjacent the heel of the shoe, thus preventing splashing or throwing of mud and water upon the outer surface of the body 13 or thereabove for deposit upon the shoe or stocking of the wearer. The guard body is detachably fixed in position by means of a tack 19 having its head 20 concealed by a strip 21 secured to the guard body 13 in any approved manner.

While I have illustrated my invention being associated with an Oxford, it is manifest that the invention may be associated with any well known type of footwear such as shoes and boots or the like.

In walking, the shoes of the individual will throw or otherwise splash matter upon the shoe or stocking and to prevent this, when my improved guard is associated with a shoe or the like, the guard body 13 is so located as to extend rearwardly from the heel of the shoe and in the path of throw of this matter.

The mud or water will not drain from the outer edges of the guard body but rather be caught by the gutter or trough and drained to a point adjacent the heel of the shoe.

It is preferable that the guard body be formed of rubber or other soft material so as not to damage articles that the heel might come into contact with but it is understood that the material from which the mud guard is formed need not be limited to a rubber composition.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

Having thus described my invention what

I claim as new and desire to protect by Letters Patent is:

A device of the class described including a substantially triangular concavo-convex member having a trough formed thereon adjacent the edges and interiorly thereof and having the end portions thereof terminating

adjacent the base portion of said member, and a heel encircling band extending outwardly from said base portion whereby said member may be secured in association with the heel of a shoe.

In testimony whereof I affix my signature.

ARTHUR G. BUGLER.
